CONTACT MOUNTING

Hermon L. Van Valkenburg, Wauwatosa, Wis., assignor to Square D Company, Detroit, Mich., a corporation of Michigan

Original application September 22, 1937, Serial No. 165,023. Divided and this application April 3, 1941, Serial No. 386,589

3 Claims. (Cl. 200—166)

This invention relates to mounting means for contact elements of electric switches, and has for its object the provision of an improved simple and economical contact mounting means.

This application is a division of my application, Serial No. 165,023, filed September 22, 1937 for Electric switch.

Other objects and features of the invention will be readily apparent to those skilled in the art from the specification and appended drawing illustrating certain preferred embodiments in which:

Figure 1 is a sectional view of the contact mounting and its cooperation with stationary contacts.

Figure 2 is an enlarged sectional view of the contact mounting.

Figure 3 is a plan view of the contact mounting.

Figure 4 is a plan view of the movable contact element.

The switching parts shown in Figure 1 include an insulating base 1 having a pair of spaced stationary contacts 2 and 3 mounted upon ledges thereof, and having cooperating therewith the movable contact plate 4 resiliently mounted within the contact mounting indicated generally at 5 which is supported upon a movable actuating element 6.

The contact mounting shown more in detail in Figures 2, 3 and 4 comprises a single piece of strip metal formed to provide a mounting foot 6, spacing leg 7, and a contact carrying part formed by the end of the leg 7 being return bent to form a rectangular structure having upper and lower walls 8 and 9, one side formed by the leg 7, and the opposite side indicated at 11. The upper wall 8 is formed with a circular depression 12. Within the rectangle formed by the walls 7, 8, 9, and 11 is mounted the movable bridging contact plate 4 having notches 14 in its opposite sides which embrace the sides 7 and 11 of the rectangle to limit normal movement of the plate 4 to a substantially straight line movement in a plane parallel to the leg 7. The contact plate 4 is provided with a projection 15 and a contact pressure spring 16 is disposed within the rectangle and maintained in place by engagement of its opposite ends with the projections 12 and 15, this spring biasing the contact 4 toward lower wall 9.

To remove the plate 4, it is only necessary to move it toward the wall 8, compressing spring

16, then to rotate it to disengage the notches 14 from the sides 7 and 11 whereupon the contact plate may be moved longitudinally of the supporting enclosure. The mounting foot 6 is provided with a threaded opening as at 17 for the reception of a securing stud such as shown at 18 in Figure 1.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. Mounting means for an electric contact comprising a unitary support formed of a strip bent at one end to provide a right angle supporting and attaching flange and having its opposite end return bent to form substantially a rectangle, a contact element mounted within said rectangle and interlocked with the side walls thereof, and spring means disposed in said rectangle between one end wall and said contact.

2. Mounting means for an electric contact comprising a unitary support formed of a strip bent at one end to provide a right angle supporting and attaching flange and having its opposite end return bent to form substantially a rectangle, a contact element mounted within said rectangle and interlocked with the side walls thereof, spring means disposed in said rectangle between one end wall and said contact, and pressed out portions on the under surface of said one end wall and on the upper surface of said contact, said spring means having its opposite ends engaging said pressed out portions so as to be retained in said rectangle.

3. Mounting means for an electric contact comprising a unitary support formed of a strip bent at one end to form a right angle supporting and attaching flange, the opposite end of said strip being return bent to form substantially a rectangle, a movable contact element insertable in said rectangle from an open side thereof and having its side edges grooved to interlock with the side walls of the rectangle when rotated into its operating position, and spring means within said rectangle biasing said contact to one extreme position.

HERMON L. VAN VALKENBURG.
